(57) **CLAIM**

The ornamental design for a diffusive multi-sampler assembly, as shown and described.

DESCRIPTION

FIG. 1 is an assembled top, left perspective view of a diffusive multi-sampler assembly, showing my new design; FIG. 2 is an assembled bottom, right perspective view thereof;

FIG. 3 is a top plan view thereof;

FIG. 4 is a bottom plan view thereof;

FIG. 5 is a left side view thereof;

FIG. 6 is a right side view thereof;

FIG. 7 is a rear view thereof;

FIG. 8 is a front view thereof;

FIG. 9 is an exploded top, left perspective view of the diffusive multi-sampler assembly of FIG. 1, the assembly including a cap, a platform and a plurality of samplers; FIG. 10 is an exploded bottom, right perspective view of FIG. 1;

FIG. 11 is an exploded left side view of FIG. 1;

FIG. 12 is an exploded right side view of FIG. 1;

FIG. 13 is an exploded rear view of FIG. 1;

FIG. 14 is an exploded front view of FIG. 1;

FIG. 15 is a top, left perspective view of one sampler of the plurality of samplers of the diffusive multi-sampler assembly of FIG. 9, in an open position;

FIG. 16 is a left side view of FIG. 15;

FIG. 17 is a right side view of FIG. 15;

FIG. 18 is a front view of FIG. 15;

FIG. 19 is a rear view of FIG. 15;

FIG. 20 is a top plan view of FIG. 15; and,

FIG. 21 is a bottom plan view of FIG. 15.

1 Claim, 11 Drawing Sheets
